TYPEWRITER.

Application filed May 26, 1924. Serial No. 716,029.

My invention relates to improvements in typewriters, and the object of the invention is to devise means for eliminating the objectionable choking or clogging effect produced by the substitution of a resilient plate for the usual hard metal or anvil ring, and to obviate the extreme accuracy necessary for producing the resilient plate hitherto constructed and thereby simplifying and 10 cheapening the manufacture, and at the same time providing a resilient stop which improves the keyboard touch, increases the speed, eliminates noise, and produces very sharp and clear printing, and also under operation preserves the alignment by reducing the wear upon the parts, and it consists essentially of a resilient plate mounted upon a type bar segment or other supporting member in such a way that the major portion 20 towards one edge is free to expand in any direction throughout its thickness, and means for securing the resilient plate to the type bar segment adjacent its opposite edge, as hereafter more particularly explained by 25 the following specification.

Fig. 1 is a perspective view of a type bar segment showing my device and the preferable means for securing my device to the segment plate.

Fig. 2 is a sectional view through the lower portion of the segment plate showing a portion of a key bar coacting therewith.

Fig. 3 is an enlarged detail showing the means for securing the resilient plate to its support.

Figs. 4 to 11 show several alternative means of permitting the free expansion of the resilient stop plate towards the printing point, and also alternative means for securing the resilient stop plate to the segment plate.

In the drawings like characters of reference indicate corresponding parts in each figure.

Referring to Figs. 1, 2 and 3, 1 includes a segment plate of ordinary construction and provided with a slotted portion 2 in which the key bars 3 are pivotally mounted in the usual way, as indicated in Fig. 2, and a 40 metal stop ring 4 forming with the portion 2 an intervening arc shaped recess or groove 5.

6 is a strip of rubber or other resilient material which is placed within the groove or recess 5. The resilient plate 6 is of less 55 width than the groove 5 so that a small clearance space is left between the stop ring 4 and the adjacent edge of the resilient plate 6 to permit of the free expansion and contraction of such edge portion towards and 60 away from the stop ring 4 when subjected to the blow of the typewriter key bar. The opposite edge, or the edge remote from the printing point is secured by suitable means to the segment plate, leaving the unattached 65 edge free to move towards the printing point as aforesaid.

There are of course many ways by which the resilient plate may be secured as above set forth to the segment plate.

I will first, however, describe the preferable means for accomplishing this result.

7 are perforations formed in the plate 6 adjacent that edge remote from the printing point and set in spaced apart positions preferably four in number, as indicated in Fig. 1 of the drawing.

8 are screws which pass through the orifices 7 and are screwed into internally threaded orifices 9 formed in that portion 80 of the segment plate 1 forming the base of the groove or recess 5. The screws 8 are provided with flat heads 10, the diametric slot 11 of which extends entirely through the head to the root of the screw shank, 85 thereby forming two notched openings at each side of the shank into which the resilient material forming the plate 6 is forced as the head is drawn into the face of the plate to compress it.

The resilient material forced into the ends of the diametric groove 11 forms a locking protuberance 6* engaging within the groove so as to prevent the turning of the screw and thereby ensure of a permanent securing 95 means for the plate 6. The stop ring 4 also has the function of protecting the upper or free edge portion of the plate 6 from dust or dirt falling downward so as to gather in between the surface of the segment plate 100 and the plate 6, such dust or dirt being shed from the stop ring 4 on to the outer edge of the plate 6 and then downward.

In Fig. 4 I have shown an alternative con-

struction similar in form to that shown in Figs. 1 to 3, with the exception that in this form the stop ring 4 is dispensed with an arc shaped band 12 provided for the purpose 5 of forming a shield to shed the dust and dirt outward so that it cannot pass into the crevice between the segment plate 1 and resilient plate 6.

In Fig. 5 I have shown a plate 13 formed 10 of resilient material, the base of which is flared outward as indicated at 14 and 15 and inserted in a correspondingly formed groove 16. In order to permit, in this construction, of the free expansion of the resilient material 15 towards the printing point, I form a recess or groove 17 adjacent the edge 14.

In Fig. 6 I have shown a resilient stop plate similar in construction to that shown in Fig. 5, but instead of the groove 17 I 20 form a complete orifice 18 extending parallel to that edge of the resilient plate adjacent to the printing point.

In the construction shown in Figs. 5 and 6, that portion of the plate extending between the sides of the groove 16, projects outward therefrom to form the surface with which the key bar contacts when operating.

In Fig. 7 I have shown a structure similar to Figs. 5 and 6, but in this figure the 30 edge portion of the resilient strip adjacent to the printing point is honeycombed, as indicated at 19, so as to impart the required expansive quality to the material when struck by the key bar.

In Fig. 8 I have shown a further alternative structure similar to Figs. 5, 6 and 7, but in this figure, in order to provide the required expansive quality to the rubber, I 40 convex the inner face of the resilient plate, as indicated at 20.

In Fig. 9 I show a resilient plate having lateral extensions 21 and 22 at its base fitting freely within a dovetailed groove 23, the edges of the portions 21 and 22 alone 45 contacting with the inclined surfaces of the groove 23, the outwardly projecting portion 24 of the resilient plate being clear of the adjacent edges of the groove and thereby forming clearance spaces 25 and 26 at each 50 side of the plate, permitting free expansion of the plate when struck by the key bar.

In Fig. 10 I show a similar construction to Fig. 5, with the exception that the edge portion of the key bar contact face towards the 55 printing point is cut away, as indicated at 27, so as to prevent the bulging over of the resilient material over the holding edge of the retaining groove in which the resilient plate is held, and thereby prevent the cutting 60 of the material which would be liable to take place if the plate were not so made.

In Fig. 11 I have shown a solid resilient plate 28 having a flaring or dovetailed base 29 fitting in the correspondingly formed 65 groove 30, the base of which is provided

with a groove recess 31 beneath the edge portion of the plate 28 adjacent to the printing point and into which the resilient material is adapted to expand when struck.

Most modern typewriters have a hard anvil or stop ring interposed in the path of the type bar travel to the printing surface, so as to overcome blurring and ensure sharp printing. This method is objectionable, because of the noise created by impact of the type bar against the metal anvil. Wear is also caused because of the violent sudden obstruction of the type bars. Replacing of the hard anvil by the substitution of a resilient elastic anvil plate has been suggested, but such means have never been put into actual practice, because the results were unsatisfactory, due to the peculiar choking action which caused an uneven touch and irregular density in the printing, this choking action being produced by the base portion of the resilient plate being closely confined in a containing groove so that the expansion movement in the resilient material is stopped, damped or choked after being struck by the key bar, from traveling through the confined portion of the plate, such portion being held from expansion by the confining boundary formed by the walls of the groove. 95

The construction above described provides means for eliminating the objectionable choking or clogging effect when a resilient plate is substituted for the usual hard anvil or stop ring.

As above indicated, the varying choking or clogging effect produced in the resilient plate is caused by confining the resilient material so that its substance cannot expand freely or move freely away from the pressure area. It is thought that the objectionable resistance is produced in the form of a compression wave which is increasingly formed as the type bar contact increases, and the objectionable effect varies with the type 110 bar speed, and is different with the adjacent bars and ones that impact against the resilient material at more distant points.

The method hitherto used for holding the resilient plate tightly in a containing or holding member which confined it and gripped its edges or otherwise restricted the expansion or extension, caused the above undesirable effects. The most common method proposed was to firmly embed the resilient plate or strip in a recess or cavity formed in a type bar segment. Such means have never withstood the demands of actual use, for the reasons above stated.

It has been found that the edges in the direction of the width of the resilient plate should be left free, or that at least one edge should be left free, preferably the edge nearest the printing point, as indicated in Figs. 1, 2 and 3 inclusive. If the edges or portion 130

of the edges must be confined, it is necessary that the resilient strip must have a hollow space in its substance, as indicated in Figs. 5 and 6, or a layer of honeycombed or less dense material in its substance near the edge that receives the most pressure, which is the edge towards which the compression wave travels, as indicated in Fig. 7, or that a space or recess be left in the material in the underside, preferably as near as possible to the edge that is closest to the printing point, as indicated in Fig. 8, or that clearance spaces be left so that a recessed or depressed portion be formed in the segment plate supporting the resilient plate located adjacent one edge of such resilient plate, as indicated in Fig. 11, in order to bring about the result desired, that is the free expansion of the resilient material when struck by the typewriter key bar.

It may be pointed out that if a solid resilient strip three sixteenths of an inch thick is confined in a recess or trough one eighth of an inch deep, it would be seen that the surface pressure causes compression to take place at the bottom and that the compression can only be relieved by the material pressing back and swelling up to the surface on each side of the type bar.

It will be seen that there are three factors present, the downward confining compacting, the surface wave in front of the advancing contact pressure and the rebound from the tightly compacted bottom material. While some of the surface material will expand over the edge of the holder, this movement is restricted by the adjoining material that cannot find a space to move into.

A type bar travels to and from the printing surface in a small fraction of a second, and it must be made clear that the functioning of a resilient stop plate must occur within such time periods, or there would be a clogging effect that is most undesirable. By allowing space for expansion or relief from pressure, manufacture is simplified, because an error of four or five one thousandths is unimportant, whereas when tightly confined, a difference of one thousandth of an inch in thickness seriously affects the proper functioning. Type bars that make a direct blow are also benefited, but the space for protrusion must be increased or both edges of the width must be left free so as to get the best results.

It might be also pointed out that a device such as I have described is applicable to various moving parts of a typewriter which would coact therewith to function in the same way such as the type bar rest, the key lever rest, or for cushioning the reciprocal movement of the escapement, because confining the resilient material causes a deadening and produces an excessive rebound which is undesirable.

Although my construction of resilient plate as above disclosed may be used alone to give satisfactory results to stop vibration, prevent blurring and accelerate the return of the type bar, it is thought best to combine it with the regular hard anvil or stop ring, as indicated before in Fig. 1, leaving a space between the two and having the hard anvil far enough back so that it will only come into effect when an extra hard blow is struck, or as a means for preventing the indenting effect of the punctuation marks.

Instead of using securing screws 11, the resilient stop plate may be secured to the segment plate by forming recesses or orifices in the plate, such as indicated at 32, into which is forced a resilient projection 33 extending from the base of the plate 13 so as to expand in the orifice 32 and thus form a locking connection, holding the plate 13 to the segment plate, as indicated in Fig. 5, or the most inert edge could be gripped by a flange of some kind, preferably consisting of little fingers gripping at several points along the most inert edge, as indicated in Fig. 4; or if desired the resilient plate may be secured to the segment plate by cementing or vulcanizing a portion or all of the underside direct to the carrying member, or various other methods might be employed which would suggest themselves to anybody skilled in this particular art.

From this description it will be seen that I have devised a very simple device which will prevent the choking or clogging effect produced in the resilient plate when struck by the type bar, which will eliminate the necessity for extreme accuracy in construction necessary in employing a resilient plate rigidly secured and confined in position upon the segment plate or other supporting member, and which thereby simplifies and cheapens the manufacture and at the same time provides a device which improves the key touch, increases the speed, eliminates type bar impact noise, and produces very sharp and clear printing, and also maintains the alignment of the type, owing to decreased wear.

What I claim as my invention is:

1. In a typewriter provided with type bars, a supporting member having an unyielding type bar contact surface, and a yielding type bar contact member secured to the supporting member which forms a bearing support therefor and secured only at its edge remote from the printing point to permit free expansion of the yielding member from the point of its attachment to the supporting member towards the printing point when subjected to the type bar blow.
2. A type bar arrester comprising a support, and a resiliently compressible member carried by the support and secured thereto along the edge remote from the printing

point of the type bar and having a cavity 10 bars, a supporting device forming a recess adjacent to its opposite or free edge to relieve the density produced in the compressible member by the type bar blow in front 5 of the type bar as the area of contact between the type bar and compressible member advances transversely thereof.

3. In a typewriter provided with typebars,

JOHN COATSWORTH REDDICK.
